COUNTERBALANCED WELL PUMPING APPARATUS

David Kane, San Antonio, Tex.

Application March 5, 1953, Serial No. 340,450

9 Claims. (Cl. 103—206)

1

The subject matter of this disclosure constitutes a continuation-in-part of that disclosed and claimed in my copending application Serial No. 271,528, filed February 14, 1952.

This invention relates generally to well pumping apparatus and more particularly to an improved actuating means adapted to be connected to the rod of a deep well pump.

According to the general principles of the present invention, a linearly reciprocable pulley block is actuated through a stroke of predetermined length by a drive means taking the form of a simple double-acting piston type motor. A frame having guide rails supporting the pulley block rises above the well head of the well and positions the block superjacent the well head in registry therewith. Pulley means are provided which cooperate with the movable block as well as with the polish rod reciprocable in the well head of the deep well pump so that the movable pulley block will be loaded in one direction by the string of sucker rods and the deep well pumping unit depending into the well from the end of the polish rod. A second pulley means is associated with the movable pulley block and includes counterweight means which effectively counter-balance the load imposed upon the pulley block by the weight of the deep well pump apparatus.

Since the effective counter-balancing of a well pumping apparatus such as has been disclosed in my copending application Serial No. 271,528 is limited at least in part by the physical height dimension of the framework rising above the well, there is specifically provided in accordance with the principles of the present invention improved means for reducing the length of stroke of the counterweights.

According to the principles of the present invention, a block and tackle ring having at least a single whip is interposed in the pulley connection between the reciprocable pulley block and the counterweights so that the ratio of the stroke of the pulley block and of the counterweights can be more closely regulated and so that the counterweight mechanism can be more effectively utilized with less wear and tear on the equipment.

It is an object of the present invention, therefore, to provide an improved actuating apparatus for a deep well pumping unit which will operate at slow speeds and which will require the expenditure of less power than has heretofore been required.

A further object of the present invention is to provide an actuating means for a deep well pumping unit which will subject the pumping

2

equipment and particularly a counterbalanced well unit to less wear and tear.

Another object of the present invention is to provide means in an actuating apparatus for a deep well pumping unit wherein the ratio of stroke between the stroke of the counterweight and the stroke of the movable pulley block may be regulated.

Yet another object of the present invention is to provide an improved counterbalancing mechanism for a deep well pumping unit.

Many other advantages, features and additional objects of the present invention will become manifest to those versed in the art upon making reference to the detailed description which follows and the accompanying sheets of drawings in which a preferred structural embodiment incorporating the general principles of the present invention is shown by way of illustrative example only.

On the drawings:

Figure 1 is an elevational view of an actuator for a well pumping unit incorporating the principles of the present invention;

Figure 2 is a side elevational view of the apparatus shown in Figure 1;

Figure 3 is a diagrammatic view illustrating the particular problem presented in connection with a counterbalanced pumping unit; and

Figure 4 is a diagrammatic view similar to Figure 3 demonstrating the advantageous operating characteristics of a pumping apparatus incorporating the principles of the present invention.

As shown on the drawings:

The apparatus of the present invention is particularly suited for actuating a deep well pumping unit used for removing liquid, such as oil or water, from a well W drilled in the ground G, the usual well head being provided and indicated at 10. The well head 10 carries a stuffing box as at 11 through which a polish rod 12 projects. It will be understood that one end of the polish rod 12 is connected to the uppermost sucker rod of a string of sucker rods having a deep well pumping unit attached thereto in depending relation therewith in accordance with conventional well pumping practice.

According to the principles of the present invention, an actuating apparatus indicated generally by the reference character 13 rises above the well W and includes a platform 14 carrying an upstanding framework structure forming a support frame 16 conveniently fabricated from metal forms such as angle irons or the like.

The support frame 16 includes two pairs of

upright guide members 17 and 18, each respective pair of guide members 17, 17 and 18, 18 being spaced apart from one another as shown in Figure 2. The guide members 17 are also spaced from the guide members 18 as shown in Figure 1 so that a vertically disposed track way is provided parallel to the axis of the well W and generally parallel to the reciprocatory path of movement of the polish rod 12.

Movably supported on the track way provided by the guide members 17 and 18 is a pulley block 19 more specifically comprising bracket means carrying a plurality of spaced apart bearings 20 journaling a shaft 21 and a shaft 22 on opposite sides of the trackway. Each of the shafts 21 and 22 is provided with roller means to engage the trackway, the shaft 21 including roller means 23 and the shaft 22 including roller means 24.

At each end of each respective shaft 21 and 22 a sheave wheel 26 is journalled, the entire sheave assembly being reciprocably movable along the trackway provided by the support members 17 and 18 with the pulley block 19.

On the under side of the pulley block 19 a frame bracket 27 (Figure 1) is provided and is connected in firm assembly with a piston rod 28 connected to a piston 29, forming a part of a double acting piston motor indicated generally by the reference character 30.

The double acting piston motor 30 preferably comprises a type of motor well known in the hydraulic arts and includes an inlet 31 at each end of a cylinder 32 regulated by a reversing valve 33 having a laterally extending actuating lever 34 (Figure 2) engaged by adjustable stops 36 and 37 carried on a stop rod 38 depending from the pulley block 19 in transversely spaced relation to the cylinder 32. Since the stop rod 38 reciprocates with the pulley block 19, proper spacing of the adjustable stops 36 and 37 fix the limit positions so that the flow of a pressurized fluid from a motor driven pump (not shown) into the conduit 39 will selectively control the operation of the motor 30.

The cylinder 32 of the motor 30 has a mounting bracket 40 on the underside thereof pinned as at 41 in pivotal relation to a stationary bracket 42 carried by the upright support members 17 and 18.

Two separate pulley ropes are provided, one for each respective pair of sheave wheels 26. One end of each of the pulley ropes 46 is made stationary by affixing same in firm assembly to the frame 16, for example, as shown in Figure 2, by affixing the end to a cable bracket 47 carried by the upright support member 18. The pulley rope is then threaded over an adjacent sheave wheel 26 and thence to an idler sheave wheel 48 journalled on each respective end of a shaft 49 carried by a bearing bracket 50 mounted in firm assembly between the upright support members 17 and 18.

From the idler sheave wheel 48, the pulley rope 46 is threaded over another of the sheave wheels 26 whereupon the other end of each of the pulley ropes 46 is connected to a cross head 51 provided with a coupling 52 which effects a connection of the cross head 51 to the polish rod 12.

The weight of the deep well pumping unit including the string of sucker rods and the polish rod 12 will tend to load the pulley block 19 in one direction. Moreover, because the pulley ropes 46 are threaded over the sheave wheels 26

and 48, the polish rod 12 and the piston rod 28 are, in effect, interconnected so that every unit of linear movement of the piston rod 28 will be matched by a corresponding or unison or linear movement of the cross head 51, and hence of the polish rod 12.

The improved counterbalancing mechanism of the present invention will now be described.

The top side of the frame 16 carries a platform 56. In opposite sides of the platform 56 are mounted brackets 57 (Figure 1) each carrying a bearing member 58 journalling the opposite ends of a shaft 59.

A drum or pulley wheel 60 is co-rotatably mounted on the shaft 59 in spaced relation to a second drum or pulley wheel 61, which is likewise co-rotatable with the shaft 59.

A pair of cable members 62 and 63, respectively, are associated with the pulley wheels 60 and 61, each of the cable members 62 and 63 carrying a connector 64 (Figure 2) at the end thereof for locking a counterweight bracket 66 in assembly therewith by means of fasteners 67. Mounted on the counterweight bracket 66 are a plurality of counterweights indicated at 68.

The opposite end of each of the cable members 62 and 63 is reeled onto the respective pulley wheels 60 and 61 and is firmly connected to each of the wheels as indicated at 69. Thus, the counterweights 68 impose a torque load on the shaft 59 by virtue of the rotative coupling action and the shaft 59 together with the pulley wheels 60 and 61 will tend to be rotated by the counterweights 68 in clockwise direction as seen in Figure 2.

In Figure 3, a diagrammatic view is shown of an actuating apparatus corresponding to that disclosed in my copending application Serial No. 271,528, filed February 14, 1952, wherein the pulley block 19 is connected to the shaft 59 by means of a pulley system including a cable member 55 reeled onto a drum or pulley wheel carried by the shaft 59 so as to rotate the shaft 59 in counterclockwise direction as seen in Figure 3.

Although the arrangement of Figure 3 affords almost an exact counterbalance insofar as the loading of the pulley block 19 is concerned through the addition or subtraction of the number of counterweights 68 on the cable members 62 and 63, it will be appreciated that the stroke of movement of the counterweights 68 will be of considerable length and, accordingly, the utility of the counterbalanced actuating apparatus for the well pumping unit will be dependent upon the physical height dimension of the framework structure rising above the well W as well as by the relative diameters of the pulley wheels 60, 61 and the reeling drum connected to the cable member 55.

In accordance with the principles of the present invention, a block and tackle rig having at least a single whip is physically interposed in the pulley system between the movable pulley block 19 and the counterweights 68 so that the stroke of the counterweights 68 relative to the stroke of the movable pulley block 19 may be effectively regulated.

As is illustrated in the particular structural embodiment of the drawings, flexible connector means are provided between the shaft 59 comprising a support bracket 70 having two strands of chain 71 and 72 extending upwardly therefrom and engaging the teeth 73 of a sprocket wheel 74 mounted inwardly adjacent each of

the pulley wheels 60 and 61. Each of the sprocket wheels 14 is corotatably mounted on the shaft 59 and the respective strands of chain 74 and 72 have their ends firmly connected to the peripheral tooth surface of each respective sprocket 14 so that the chains 74 and 72 can be threaded over the teeth 73 to impose a rotative coupling load on the shaft 59 tending to rotate the sprockets 14 together with the shaft 59 in a counterclockwise direction as seen in Figure 2.

The mounting bracket 70 carries a pair of spaced pins 76 adjacent the under side thereof each mounting a sheave 77.

It will be understood that the term "sheave" as used in describing the member 77 is employed in a generic sense and identifies any rotatable member operable as a pulley wheel. In the illustrated embodiment, the sheave 77 takes the form of a sprocket having circumferentially spaced teeth.

In the illustrated embodiment, the block and tackle attachment interposed between the pulley block 19 and the shaft 59 includes a single whip. In other words, the pulley rope means provided for the block and tackle arrangement includes a single strand for each of the respective sheaves 77 identified by the reference numeral 78. Each respective strand 78 has a stationary end 79 connected to the platform 16 by a bracket connector 80 mounted in firm assembly on the upright support members 17 and 18.

Each strand 78 is further provided with a movable end 81 connected to the movable pulley block 19.

In the illustrated embodiment the strands 78 include a double length chain, one chain being threaded over each respective sprocket 77 and engaging the teeth thereon.

By virtue of the arrangement thus provided, the movable pulley block 19 and the counterweights 68 as well as the polish rod 12 and the string of sucker rods and the deep well pumping unit attached thereto will all be reciprocated in unison with the actuation of the piston 29 in the cylinder 32 of the motor 30.

The advantageous operating characteristics of the present invention are clearly demonstrated in Figure 4 of the drawing.

As will be noted upon comparing Figures 3 and 4, the movement of the support brackets 70 together with the sheaves 77 in the spacing dimension between the shaft 59 and the movable pulley block 19 will be quite small in quantitative value as is illustrated by the difference between the full line position of the bracket 70 and the dotted line position thereof. Accordingly, the interposition of the block and tackle rig in the pulley connection between the pulley block 19 and the counterweights 68 will not interfere with the linear reciprocation of the pulley block 19. Because of such interposition, however, the stroke of the counterweights 68 will be considerably reduced without reducing the corresponding stroke of the well pumping unit. Thus, ordinary framework constructions may be effectively utilized without increasing the overall height thereof.

With an arrangement as herein described, the increased length of stroke of the well pumping unit and the decreased length of stroke of the counterweight enables the power means to be reciprocated at slower speeds than have been heretofore required and because of the mechanical advantages effectively exploited through the utilization of the various pulley systems described, the power requirements for successful

operation of the actuating apparatus are actually reduced.

Furthermore, the increased length of stroke of the well pumping unit and the decreased length of stroke of the counterweights minimizes wear and tear on the pumping apparatus, thereby cutting down on the necessity of providing expensive maintenance.

Although various minor structural modifications might be suggested by those versed in the art, it should be understood that I wish to embody within the scope of the patent warranted hereon all such modifications as reasonably and properly come within the scope of my contribution to the art.

I claim as my invention:

1. In a counterbalanced deep well pumping apparatus of the type having a rod connected to a deep well pump unit and a counterweight, a reciprocating motor having a linearly movable reciprocating drive member, a first pulley means including a compounded pulley rope connected to said drive member and said rod to move the pump unit in unison with the drive member, and a second pulley means connected to said counterweight and to said drive member to move the counterweight in unison with the drive member, said second pulley means including a block and tackle having at least a single whip connected to said drive member to reduce the stroke of the counterweight.

In combination, a counterbalanced deep well pumping unit having an actuating rod reciprocable through a predetermined stroke and a counterweight movable in unison with said rod through a stroke of predetermined length, a drive means having a linearly movable reciprocating drive member, a first pulley connector operatively connected between said rod and said drive member to reciprocate said rod in unison with said drive member, and a second pulley connector operatively connected between said counterweight and said drive member to reciprocate said counterweight in unison with said drive member, said second pulley connector including a block and tackle interposed therein and having at least a single whip connected to said drive member for reducing the stroke of said counterweight.

3. In combination, a counterbalanced deep well pumping unit having a reciprocating actuating rod connected thereto, a drive means having a linearly movable reciprocating drive member, a compound pulley connection operatively connected between said rod and said drive member, the stroke of said rod and the stroke of said drive member being in proportion to the compounding of said pulley connection, whereby said rod will be reciprocated in unison with said drive member, and a counterweight mechanism counter-loading said drive member and comprising a rotatable shaft, weights having a flexible connector means wound on said shaft to torque load said shaft in one direction, pulley block means including pulley wheel means having a flexible connector means wound on said shaft to torque load said shaft in an opposite direction, said pulley block means including a pulley rope means having one end stationarily connected and movable and trained over said pulley wheel means and being connected to said drive member, thereby to reduce the stroke of said weights.

4. Actuating means for a deep well pumping unit of the type having a polish rod reciprocable in a well head, comprising, a linearly recipro-

cable pulley block, pulley wheels on said block, pulley means including a pulley rope threaded over said pulley wheels on said pulley block and having one end connected to said polish rod of the deep well pump unit, thereby to load the pulley block in one direction, continuous biasing means connected to said pulley block to load the pulley block in an opposite direction, thereby to counterbalance the load on said pulley block, said continuous biasing means including linearly movable counterweights, a pulley means connecting said counterweights to said pulley block and including a block and tackle rig having at least a single whip, and drive means connected to said pulley block to selectively reciprocate said pulley block for actuating said deep well pump and for moving said counterweights all in unison.

5. In a deep well pumping apparatus, a pulley block, pulley wheels on said block, guide means supporting said block for linear reciprocation, pulley means including a pulley rope threaded over said pulley wheels on said pulley block and having a stationary end, a polish rod reciprocable in a well head of a deep well pump, and a movable end on said pulley rope connected to said polish rod of the deep well pump, thereby tending to load the pulley block for movement in one direction, a pulley wheel means superjacent said guide means, a counterweight movable through a stroke of predetermined length in a direction parallel to the stroke of said polish rod, pulley rope means cooperating with said pulley wheel means and being operatively connected to said pulley block and to said counterweight to counterbalance the pulley block, said pulley rope means including a block and tackle rig having at least a single whip to reduce the stroke of said counterweight, and drive means to selectively reciprocate said pulley block for operating the deep well pump and for moving the counterweights all in unison.

6. Actuating means for a well pumping apparatus rising above a well comprising a movable pulley block, guide rails supporting said pulley block for linear reciprocating movement, a first pulley means cooperating with said movable pulley block and connected to the rod of a deep well pump depending into the well, whereby the pulley block is loaded in one direction, a stationary pulley block, a second pulley means cooperating with said stationary pulley block, said second pulley means being connected to said movable pulley block, counterweight means connected to said second pulley means to counterbalance the movable pulley block and including movable weights translatable on a path of movement generally parallel to the movement of said polish rod, a block and tackle rig interconnecting said movable pulley block and said weights to reduce the effective stroke of the counterweights, and drive means to reciprocate the pulley block for operating the deep well pump and for moving the counterweights all in unison.

7. Actuating means for a well pumping apparatus rising above a well, comprising, a frame, guide means on said frame, a pulley block carried by said guide means for linear reciprocation thereon, a pair of pulley wheels on said pulley block, a cable trained over each of said pulley wheels, one end of each of said cables being stationarily connected to said frame, a cross head member connected to the other end of each

of said cables, said cross head member connected to the rod of a deep well pump depending into the well, thereby to load the pulley block in one direction, bearing means on said frame, a shaft 5 journaled in said bearing means, drum means carried by said shaft and having flexible cable means reeled thereon, a plurality of counterweights movable along an axis of movement generally parallel to the axis of the well and being connected to the free end of said flexible cable means, sheave means carried by said shaft and a second flexible cable means reeled on said sheave means and being connected to said pulley block, said weights arranged to counterbalance said 10 pulley block, said second flexible cable means including a block and tackle rig to reduce the effective stroke of said counterweights, and drive means to reciprocate said pulley block for operating the pump and for moving the counterweights in unison therewith.

8. An actuating means for a well pumping apparatus comprising a frame adapted to overlie a well, a guide means on said frame, a pulley block carried by said guide means for linear reciprocation thereon, a pair of shafts on said pulley block, a pulley wheel on the ends of each of said shafts, bearing means on said frame, a shaft journaled in said bearing means, a first drum means carried by said shaft, a first cable means 25 reeled on said first drum means and having a counterweight connected to the end thereof to rotate the shaft in one direction, a second drum means carried by the shaft, comprising toothed sprocket wheels, a second cable means reeled on said second drum means and comprising a double strand chain having one end connected to said sprocket wheels and the other end connected to said pulley block so that movement in one direction of said pulley block will tend to rotate 30 the shaft in an opposite direction, said second cable means having a block and tackle rig interposed in the length thereof to reduce the stroke of said counterweights, and drive means to reciprocate said pulley block, said pulley block having 35 a deep well pumping unit having a rod depending into the well, said rod operatively connected to said pulley means thereby to operate the well in unison with movement of the pulley block.

9. In a well pumping actuating apparatus of the type having a reciprocating motor with a linearly movable reciprocating drive member, well pumping means loading said drive member in one direction, and counterweight means counterbalancing said reciprocating drive member, said counterbalancing means including a plurality of counterweights, pulley means operatively connecting said reciprocating drive member and said counterweights to move said counterweights 40 along a path of movement parallel to the reciprocating path of said drive member and including a block and tackle rig having at least a single whip to reduce the effective stroke of the counterweights.
